UNITED STATES PATENT OFFICE.

THOMAS T. McNISH, OF ALLEGHENY, PENNSYLVANIA.

SEALING BOTTLES.

SPECIFICATION forming part of Letters Patent No. 683,885, dated September 26, 1899.

Application filed January 22, 1898. Serial No. 667,636. (No model.)

To all whom it may concern:

Be it known that I, THOMAS T. McNISH, a citizen of the United States, residing at Allegheny, in the county of Allegheny and State of Pennsylvania, have invented or discovered 5 certain new and useful Improvements in Sealing Bottles, of which improvements the following is a specification.

The invention described herein relates to 10 certain improvements in sealing bottles, and has for its object a construction whereby an internal or external closing device may be secured in position in such manner as to require the breaking of an integrally-formed part 15 necessary to the closure of the bottle before access can be had to the contents of the latter.

In general terms the invention consists in 20 shoulders formed on the bottle and the closing device and a key or locking-piece engaging said shoulders and rendered inaccessible by the closing or sealing of the bottle.

In the accompanying drawings, forming a 25 part of this specification, Figure 1 is a view, partly in section and partly in elevation, of a bottle having my improvement applied thereto. Fig. 2 is an elevation of the upper portion of a bottle, showing the cap in position. Fig. 3 is a sectional view, the plane of section being indicated by the line $x-x$, Fig. 1. Fig. 30 4 is a detail view of one form of locking device; and Fig. 5 is a sectional view on the line $y-y$, Fig. 1.

In the practice of my invention the upper 35 portion of the neck b of the bottle is preferably made tapering, but may be made cylindrical, and is provided at a suitable distance from its upper end with a shoulder c to limit the downward movement of the closing-cap a .

As shown, this cap is made of an internal 40 shape and dimension corresponding to the external shape and size of the upper portion of the neck, so as to fit easily, but not with any great amount of friction, over such upper portion of the neck. At a suitable 45 point between the shoulder c and the upper end of the neck the latter is provided with a groove e , extending entirely around it, and the cap a is also provided with a groove d , so located that when the cap is placed in position, as shown in Figs. 1 and 2, the grooves 50 in the cap and neck will lie in, or approximately in, the same plane. Before placing

the cap on the bottle the locking device or key f is placed within the groove in the cap, so as to be carried down into line with the 55 groove in the neck. This key or locking device is preferably made in the form of an elliptical ring, but may be made of any other shape—such as epicycloidal, square, triangular, &c.—which will insure the engagement 60 of portions of the ring with the groove on the cap and other portions with the groove in the neck. When the locking-key or locking device is made of elliptical shape, the major axis thereof is of a length equal, or approxi- 65 mately equal, to the diameter of the groove in the cap, while its minor axis is of a diameter not greater than the diameter of the groove in the neck, as clearly shown in Fig. 3.

In sealing the bottle the locking device is 70 placed in position in the groove in the cap, which is then slipped over the bottle-neck, the upper end of the latter spreading the ring or locking device in the direction of its shorter axis, so that the ring can be carried down by 75 the cap. As soon as the ring comes into alignment with the groove in the neck it will contract or spring back toward normal position, so that portions of it adjacent to the ends of its shorter axis will enter the groove in the 80 neck, while the portions adjacent to the ends of its major axis will remain in the groove in the cap, so that the latter will be firmly locked in position on the bottle.

It is characteristic of my improvement that 85 when secured in position the locking device will be inaccessible, and the cap cannot be removed to permit access to the contents of the bottle without a rupture of the cap or portion of the bottle.

The cap may be so proportioned that its 90 inner wall or lower end will form a tight joint with the neck of the bottle, so as to be in and of itself an effective closing device for the bottle; but it is preferred to employ the 95 cap as a means for holding a cork or other stopper g in position in the bottle. In such case the stopper is inserted before placing the cap in position and is forced to a tight seat in the neck by the movement of the cap to locking position.

The cap is so constructed that when struck on its upper end it will fracture along lines parallel or substantially parallel with the axis

of the cap, thereby avoiding all splintering such as occurs when the caps are formed of glass, which even when grooved to determine the line of rupture will break in other directions. Any material having a parallel or approximately fibrous structure, such as wood, is preferably employed in the manufacture of the caps, although the rupture of the cap in lines parallel with the axis of the cap can be insured by cutting longitudinal grooves *i* in the inner wall of the cap, as shown in Fig. 5. In the manufacture of the cap care is taken that the fibers of the wood shall be parallel or approximately parallel with the axis of the cap, so that by a sharp blow on the end of the cap (preferably provided with a knob *h* for that purpose) the cap will split longitudinally into two or more pieces, which will drop away from the neck of the bottle. When the cap is grooved to facilitate rupture, the grooves should be so located that the pieces will not be greater transversely than a semicircle and will not therefore cling to the neck.

The cap *a* is made a little longer than the portion of the neck above the shoulder *c*, so that the lower end of the cap will have a bearing on such shoulder when in locked position. As the shoulder is formed by thickening the glass of the neck portion, the shoulder will form a solid abutment or support for the cap when the latter is broken.

It is characteristic of my improvement that it can be applied to bottles without materially changing the shape or construction thereof, it only being necessary to form a groove in the neck of the bottle for the reception of the locking device. It is also characteristic of my improvement that the bottle is not in any way injured by the removal of the cap and can be used again, a new securing-cap being supplied.

It will be observed that the portions of the grooves in the cap and neck which are operative to hold the former in position are the lower wall of the groove in the cap and the upper wall of the groove in the neck, said walls being in effect shoulders, so that the purposes of my improvement can be attained by the employment of projections on the neck and cap, such projections being so located

that when the cap has been placed in position the projection on the latter will pass a sufficient distance beyond the projection on the neck for the interposition of the locking device between them.

55

I claim herein as my invention—

1. The combination of a bottle-neck provided with a supporting-shoulder, and having projections above the shoulder, a stopper a wooden cap frangible on two or more lines parallel or approximately parallel with its axis and having its grain also approximately parallel thereto and adapted to fit over the neck and rest upon the shoulder, and provided with an internal projection, and a spring locking device engaging the projections on the neck and cap and entirely inclosed by the latter, substantially as set forth.

60

2. The combination of a bottle-neck provided with a supporting-shoulder and having projections above the shoulder, a stopper a cap formed of wood having its fibers parallel or approximately parallel with the axis of the cap and adapted to fit over the neck and resting upon the shoulder thereof and provided with an internal projection, and a spring locking device engaging the projections on the neck and cap, and entirely inclosed by the latter, whereby said cap may be readily broken by a blow delivered on its upper end substantially as set forth.

70

3. The combination of a bottle-neck provided with a supporting-shoulder and having projections above the shoulder, a stopper a wooden cap grooved longitudinally on two or more lines parallel or approximately parallel with its axis and having its fibers also approximately parallel therewith and adapted to fit over the neck and rest on the shoulder of the bottle and provided with an internal projection, and a spring locking device engaging the projections of the neck and cap and entirely inclosed by the latter, substantially as set forth.

80

In testimony whereof I have hereunto set my hand.

THOMAS T. McNISH.
